Specification for Design.

Patented July 15, 1919.

Application filed February 12, 1919. Serial No. 276,671. Term of patent 14 years.

To all whom it may concern:

Be it known that I, CLARENCE WRIGHT, a citizen of the United States of America, residing at Racine, in the county of Racine and State of Wisconsin, have invented a new, original, and ornamental Design for Heels and Lifts for Boots, Shoes, or Articles of Similar Nature, of which the following is a specification, reference being had to the accompanying drawings, forming part thereof.

In the drawings:

Figure 1, is a bottom plan view of a heel lift embodying my new design:

Fig. 2 is an edge view, and Fig. 3, an end view thereof.

I claim:

The ornamental design for a heel or lift for boots, shoes, or articles of similar nature substantially as shown.

CLARENCE WRIGHT.
